UNITED STATES PATENT OFFICE.

ALBERT R. KAMPFF, OF NEW YORK, N. Y.

THAWING DEVICE FOR HYDRANTS.

1,253,692.

Specification of Letters Patent. Patented Jan. 15, 1918.

Application filed July 21, 1917. Serial No. 181,961.

To all whom it may concern:

Be it known that I, ALBERT R. KAMPFF, a citizen of the United States, and a resident of New York city, in the county and State of New York, have invented certain new and useful Improvements in Thawing Devices for Hydrants, of which the following is a specification.

This invention relates to a device of novel 10 construction by means of which a hydrant or fire plug may be readily thawed out when frozen. The invention consists in the various features of novelty more fully pointed out in the specification and appended claim.

15 In the accompanying drawing:

Figure 1 is a longitudinal section partly in side view of a hydrant provided with a thawing device embodying my invention;

Fig. 2, longitudinal section on line 2—2
20 Fig. 1;

Fig. 3, a cross section on line 3—3 Fig. 1,
and

Fig. 4, a plan of the thawing device detached, showing the pipes in section.

25 The stand pipe 1 of the hydrant, extends as usual several feet beneath the surface level 2, and is connected at its lower end by an elbow 3 with the service pipe 4 controlled by a valve 5, the valve spindle 6 passing axially through the stand pipe. These parts are of the conventional or suitable construction and do not form part of my invention. In case the valve leaks, water will accumulate in the lower portion of the stand pipe, 30 and under a sufficiently low temperature this water will turn into ice, which will bind the valve spindle and thus render the hydrant inoperative. To quickly thaw out this ice is the object of the present invention.

40 Within the lower end of the stand pipe, and within its freezing zone, directly above valve 5, there is fitted an annular vessel 7, which is split or divided longitudinally and is shown to be furnished with a pair of upright end walls 8, which are spaced a slight distance from each other. Vessel 7 is formed of an arched outer wall 9 (that closely hugs the inner face of the stand pipe) an inner concentric wall 10 (within 45 which spindle 6 is centered), a curved bottom 11, and a divided annular top plate or head 12. In proximity to each of its end walls 8, vessel 7 is provided at its upper end with inwardly extending pockets 13, that 50 communicate respectively with the lower ends of a pair of pipes 14 which are tapped

into head 12 and project upwardly through the stand pipe, along spindle 6. Either one of these pipes 14 forms an inlet for steam or hot water, which constitutes the thawing 60 medium, while the other pipe forms the outlet for said medium. At their upper ends pipes 14 are furnished with diverging branches 15, that open through diametrically opposed points of stand pipe 1. These 65 branches carry washers 16 and caps 17, which caps are removed when one of said branches is coupled to the engine or other source of supply of the thawing medium, while the other branch constitutes an outlet 70 for said medium.

At its rounded bottom, vessel 7 communicates by means of an inwardly extending branch 18, with a drain- or suction pipe 19, which is partially encompassed by vessel 7, 75 and extends a distance up within stand pipe 1. At its upper end, pipe 19 is connected to a branch 20, which opens outwardly preferably through the back of the hydrant. This branch is shown to carry an inner lock nut 80 21, an outer washer 22, and a cap 23 which is threaded on the protruding end of the branch.

In use, hot water or steam which constitutes the thawing medium and which is admitted through one of the pipes 14, will flow into vessel 7, so as to fill the same and after having passed completely around the vessel, will be discharged through the other pipe. In this way the thawing medium, while 85 within the pipes 14, and also while within the vessel 7, will heat up an extensive area of thawing surface by means of which the stand pipe together with the valve spindle may be quickly and effectively thawed out. 90 After the thawing out operation has been completed or at any time thereafter, the water may be readily removed by a pump 95 coupled to the drain pipe 19.

My improved thawing device possesses 100 numerous advantages: By means of the annular thawing vessel described, an extensive chamber will be provided and any water remaining therein, will on freezing, not be liable to burst the same, as is the case with 105 thawing coils. The vessel owing to its upright division must be entirely traversed by the heating medium, and forms, together with the inlet and outlet pipes, an extensive 110 heat radiating surface. As the vessel is enclosed by the stand pipe of the hydrant, it comes into direct contact with the ice, so as

to operate to the greatest advantage, in contradistinction to those devices which are arranged exteriorly of the stand pipe. The rounded bottom more effectively withstands 5 the extensive attack of the ice and provides a lower channel by which the vessel may be thoroughly drained. Finally, the device can be readily installed in hydrants of ordinary construction, subsequent to their setting up 10 and without requiring extensive alterations.

I claim:

A hydrant having a stand pipe, a valve

and a valve spindle, combined with a vertically divided annular vessel inclosed within the lower end of said stand pipe and encompassing said spindle, an inlet pipe, an outlet pipe and a drain pipe located within the stand pipe, said inlet pipe, outlet pipe, and drain pipe communicating at their lower ends with said vessel, and adapted to open outwardly at their upper ends through said stand pipe. 15 20

ALBERT R. KAMPFF.
